UNITED STATES PATENT OFFICE

THOMAS J. NOONAN, OF BAYONNE, NEW JERSEY, ASSIGNOR TO J. EDWARD OGDEN COMPANY, INC., OF EAST ORANGE, NEW JERSEY, A CORPORATION OF NEW JERSEY

EXPANSION SHIELD

Application filed October 30, 1931. Serial No. 572,007.

This invention relates to expansion shields for use in forming anchorages in brick, stone or cementitious material to directly receive and retain a threaded element.

One of the commonest forms of expansion shields is the two-section or two-way shield in which the sections are laterally expanded in opposite directions. This shield is effective and efficient under most conditions but under certain conditions tends to split the material in which it is set or expanded since all of the expansion stress is exerted in opposite directions. Moreover, as the two sections are separated or spread apart during expansion there are formed gaps therebetween where there is no gripping action.

This invention has for its salient object to provide an anchor that is simple and practical in construction, comprises a minimum number of parts and will form an efficient anchorage.

Another object of the invention is to provide an anchor or expansion shield so constructed and arranged that the expansion stress will be distributed in more than two directions and a greater gripping and holding power will be secured than is secured with the two-way expansion shield.

Another object of the invention is to provide an anchorage having the characteristics and advantages set forth that can be economically manufactured.

Further objects of the invention will appear from the following specification taken in connection with the drawing which forms a part of this application, and in which

Fig. 1 is an elevational view of an expansion shield constructed in accordance with the invention;

Fig. 2 is an end elevation of the shield shown in Fig. 1;

Fig. 3 is a longitudinal sectional elevation taken at right angles to Fig. 2 and substantially on line 3-3 of Fig. 2;

Fig. 4 is a transverse sectional elevation taken substantially on line 4-4 of Fig. 1;

Fig. 5 is an elevational view of one section of the shield looking at the inside of the shield;

Fig. 6 is a similar view of the other section of the shield;

Fig. 7 is an end elevation of one end of the expanding element or nut; and

Fig. 8 is a side elevation of the nut.

The invention briefly described consists of an expansion shield comprising two sections, one of the sections having a plurality of expansible portions. The shield is further provided with means arranged to contact with the expanding element or nut to prevent rotation of the nut as the latter moves into the shield and expands the shield.

Further details of the invention will appear from the following description.

In the form of the invention illustrated in the drawing there is shown an expansion shield comprising a pair of sections A and B. The shield sections are so formed as to provide a groove 10 adjacent the outer end and a groove 11 nearer the longitudinal center thereof. One of the sections, such as A, is provided with a pair of tabs 12 and 13 which seat in the portion of the groove 11 formed in the other section.

The section B is provided along its longitudinal edges with a pair of fingers 15 and 16 having inturned ends 17 which extend over the outer end of the expanding element or nut 18.

The section A has longitudinal slits 21 and 22 which form an elongated finger 23 having inturned end portion 24. The slits divide the section A into expansible portions C and D which are separated by the finger 23.

The expanding element or nut 18 is provided with three tapered projecting portions 25, 26 and 27 which are disposed between the fingers 15, 23 and 16 and the portions of the nut disposed within these fingers and indicated at 28 are cylindrical.

The section B is tapered at its inner end, as shown at 30, and the expansible portions C and D of the section A are also tapered at 31 and 32. The tapered portions of the nut are disposed within the tapered portions of the shield and coat therewith and force the expansible portions of the shield

laterally as the nut is drawn into the shield. The fingers 15, 16 and 23 which are disposed outside the cylindrical portions 28 of the nut and between the projecting portions 25, 26 and 27 prevent the nut from rotating as it is drawn into the shield.

When the shield is expanded the expanding stress will be exerted in three directions, or in other words, against the section B and 10 against the portions C and D of the section A. In addition to distributing the expanding stress in this manner the shield will have a firmer gripping action due to the 15 three-way expansion. Furthermore, since the shield is formed in two sections it can be readily cast without necessitating the use of a core or cores which would be required if the shield were formed in three sections, integrally connected.

20 Although one specific embodiment of the invention has been particularly shown and described it will be understood that the invention is capable of modification and that changes in the construction and in the arrangement of the various cooperating parts may be made without departing from the spirit or scope of the invention, as expressed in the following claims.

What I claim is:

- 25 1. A two section, three-way cast metal expansion shield comprising a pair of semi-cylindrical sections, one section only comprising a pair of expandable portions, and an expanding member in said shield having tapered portions arranged to expand the two expandable portions and the other shield section.
- 30 2. A two section, three-way cast metal expansion shield comprising a pair of semi-cylindrical sections, one section only comprising a pair of expandable portions, and an expanding member in said shield having

tapered portions arranged to expand the two expandable portions and the other shield section, said last named section provided with a pair of fingers engaging the expanding member for preventing rotation thereof.

3. A two section, three-way cast metal expansion shield comprising a pair of semi-cylindrical sections, one section only comprising a pair of expandable portions, and an expanding member in said shield having tapered portions arranged to expand the two expandable portions and the other shield section, said last named section provided with a pair of fingers engaging the expanding member for preventing rotation thereof and 70 said other section having a finger intermediate the edges thereof.

4. A two section, three-way cast metal expansion shield comprising a pair of semi-cylindrical sections, one section only comprising a pair of expandable portions, and an expanding member in said shield having tapered portions arranged to expand the two expandable portions and the other shield section, said last named section provided with 75 a pair of fingers engaging the expanding member for preventing rotation thereof and said other section having a finger intermediate the edges thereof and between the expandable portions of said section.

5. A two section, three-way cast metal expansion shield comprising a pair of semi-cylindrical sections, one section only comprising a pair of expandable portions, and an expanding member in said shield having tapered portions arranged to expand the two expandable portions and the other shield section, said last named section provided with a pair of fingers adjacent the edges of said section and engaging the expanding member 100 for preventing rotation thereof.

THOMAS J. NOONAN.
